TWO-WAY BULKHEAD DOOR
CONSTRUCTION

Charles J. Roos, Muskegon, Mich.

Application December 14, 1950, Serial No. 200,811

2 Claims. (Cl. 20—16)

1

This invention relates to building construction, and aims to provide a two-way bulkhead door construction wherein the door sections when moved to close a hallway will check wind and pressure occurring from explosive forces, thereby providing an appreciable degree of protection to the occupants of buildings equipped with doors constituting the subject matter of the present invention.

An important object of the invention is to provide a double bulkhead door construction including transverse bars which will withstand severe pressures directed thereto at either side of the door, the transverse bars providing an effective brace against excessive pressures to maintain the hallway closed for protection of the building.

Still another object of the invention is to brace the doors along their hinged ends as well as at the latch sides of the door frames thereof, providing stronger resistance against pressures from either direction.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

Referring to the drawing

Figure 1 is a perspective view illustrating a portion of a hallway of a building, showing bulkhead doors, constructed in accordance with the invention as mounted therein.

Fig. 2 is a transverse sectional view through a wall and door opening, guarded by bulkhead doors constructed in accordance with the invention.

Referring to the drawing in detail, the reference character 5 indicates generally a hallway of which the floor 6, side walls 7 and ceiling 8 form a part.

Extending inwardly from one of the side walls, is a vertical enlargement or beam 9 formed with a vertical rib 10 disposed intermediate the side edges thereof, the vertical rib 10 having semi-circular recesses 11 formed in the side edges thereof.

The reference character 12 indicates closures which are hingedly connected to the vertical enlargement 9 by means of hinges 13.

As shown, the closures 12 are provided with transverse rods 14 which are disposed in vertical spaced relation with respect to each other, the rods extending throughout the entire widths of the closures.

These rods are so disposed that when the closures 12 are moved to their closed positions, as shown by Fig. 2 of the drawing, the rods will move into the semi-circular recesses 11 to brace the doors or closures against excessive pressures caused by wind or explosions.

Extending from the opposite side wall 7, is

2

the wall 15, which is provided with a vertical rib 16 formed intermediate its side edges, the rib 16 extending throughout the height of the door opening. This rib 16 is formed with semi-circular recesses 17 which are so located that the outer ends of the rods 14, will move thereinto, bracing the outer or free edges of the doors against wind pressures or pressures caused by explosions.

It will of course be understood that these closures or doors are provided with the usual latches 18 and handles 19, whereby the closures may be operated, and secured in their closed positions when it is desired to divide the hallway into bulkheads.

From the foregoing it will be seen that due to the construction shown and described, I have provided a pair of hinged closures which are so constructed and arranged that when they are moved to their closed positions, the hallway in which the closures are positioned, will be divided into bulkheads to prevent free passage of winds and pressures through a hallway, which would tend to damage the building.

Having thus described the invention, what is claimed is:

1. Means for dividing the hallway of a building into compartments comprising vertical ribs carried by and extending into the hallway from opposite side walls thereof, opposite side edges of the ribs having vertically spaced semi-circular recesses opening therethrough, closures mounted on the vertical ribs, transverse rods secured to opposite side faces of said closures, said rods being disposed in vertically spaced relation with respect to each other and being adapted to enter the semi-circular recesses when the closures are moved to their closed position for bracing the closures against buckling under pressures directed thereagainst.

2. Means for dividing the hallway of a building into compartments comprising vertical ribs carried by the walls of the building and extending from the floor to the ceiling of the hallway, closures mounted on the vertical ribs to swing from an inactive position in which they lie at an angle to the ribs to an active position in which they lie parallel with and extend between the ribs, said ribs providing stops against which the hinged closures engage where said closures are in active position, said ribs having recesses in the opposite side edges thereof, and brace rods carried by the closures and entering the recesses when the closures are moved to their active position for holding the closures against buckling under pressures directed thereagainst.

CHARLES J. ROOS.
